MACHINE FOR OPERATING ON SHOES

Bernhardt Jorgensen, Marblehead, Mass., assignor to United Shoe Machinery Corporation, Flemington, N. J., a corporation of New Jersey

Application December 21, 1945, Serial No. 636,289

52 Claims. (Cl. 12—1)

1

This invention relates to machines for operating on shoes, and is herein shown as applied to a toe-lasting machine constructed generally as disclosed in United States Letters Patent No. 2,324,509, granted on July 20, 1943, on an application of mine, but modified in some respects as further disclosed in other Letters Patent hereinafter mentioned. It is to be understood, however, that in various novel aspects the invention is not limited to the illustrative embodiment.

The above-mentioned lasting machine is a fluid-operated machine including wipers which in the course of a cycle of automatic operations of the machine wipe the lasting margin of the toe end of the upper inwardly over an insole where it is secured to the insole by cement. The machine comes automatically to a stop to permit the wipers to remain for a few seconds in pressure-applying relation to the overwiped margin of the upper while the cement is setting, after which it is again started and completes its cycle, releasing the shoe. One object of this invention is to increase the output of the machine by reducing the time required for the wipers thus to dwell on the margin of the upper. To this and other ends, there is herein shown, as an attachment on the machine, novel means to which the shoe is presented by the operator immediately after the toe-lasting operation for further pressing the margin of the upper on the insole until the cement has more firmly set. This means comprises a pressing plate formed to overlie the marginal portion only of the shoe bottom, and a shoe rest arranged to engage the top of the fore-part of the shoe and movable while the operator supports the shoe to force it against the plate, the latter being flexible to permit it to conform to the contour of the shoe bottom. The shoe rest is thus operated in response to the presentation of the shoe to the plate by fluid obtained from an accumulator which is charged by the fluid-pressure system of the lasting machine, the shoe when thus presented closing an electrical switch which controls the circuit of a valve-operating solenoid. This circuit is broken automatically by the next cycle of operations of the lasting machine near the end of the cycle to cause the shoe rest to release the shoe. To insure that the above-mentioned switch, after it has been closed by the shoe, will remain closed regardless of any slight displacement of the shoe, mechanism is provided for subjecting it automatically to closing force independently of the shoe.

Since the lasted toe end of a shoe of the type herein shown usually needs to be trimmed to re-

2

move surplus material from the marginal portion of the upper at a distance from the edge of the shoe bottom near the end of the toe, the invention further provides novel means arranged to cooperate with the above-mentioned pressing plate to accomplish that result. In the construction shown a cutter is moved bodily lengthwise of the shoe along the shoe bottom toward the end of the toe to trim off surplus upper material extending beyond the plate, the cutter being thus operated by a cutter support which swings about an axis extending widthwise of the shoe but being movable relatively to the support and held yieldingly in contact with the plate in the upper-trimming operation. Operative movement is imparted to the cutter support by fluid-pressure means to which, as herein illustrated, fluid is conveniently admitted from the fluid-pressure system of the lasting machine in the course of the next cycle of operations of the machine. In order to dispose of the waste material removed from the upper the invention further provides novel ejector mechanism, this mechanism being operated, in the construction shown, in response to return movement of the cutter support after the trimming operation.

The above and other features of the invention, including novel shoe-positioning means, novel means for guiding the shoe into position to be operated on, and various novel details of construction and combinations of parts, will now be more particularly described with reference to the accompanying drawings and thereafter pointed out in the claims.

In the drawings,

Fig. 1 is a view in front elevation of the greater portion of the toe-lasting machine to which the invention is herein shown as applied, parts being broken away;

Fig. 2 is a plan view on an enlarged scale of a portion of the structure shown at the lower left-hand side of Fig. 1, the frame of the machine being sectioned;

Fig. 3 is a section on the line III—III of Fig. 2;

Fig. 4 is a plan view on an enlarged scale of a portion of the machine, with parts broken away;

Fig. 5 is an enlarged view in elevation, from the front of the machine, of the toe-pressing and trimming attachment shown at the left-hand side of Fig. 1;

Fig. 6 is a view mainly in left-hand side elevation of the toe-pressing and trimming means;

Fig. 7 is a section on the line VII—VII of Fig. 5;

Fig. 8 is a section on the line VIII—VIII of Fig. 6, with parts broken away;

Fig. 9 is a view similar to Fig. 8, but showing also a portion of the toe-trimming means in the course of its action on a shoe;

Fig. 10 is a view in vertical section of a portion of the toe-pressing and trimming means, with the trimming means positioned as in Fig. 9;

Fig. 11 is a vertical section at right angles to that of Fig. 10, showing the parts in the same positions;

Fig. 12 is a view similar to Fig. 10 with the parts as they appear after the beginning of the return movement of the trimming cutter;

Fig. 13 is mainly a vertical sectional view showing a valve involved in the operation of the trimming means and the valve-operating mechanism; and

Fig. 14 is a diagrammatic view of the fluid-pressure generating and controlling means with which the lasting machine is provided.

As disclosed in the previously mentioned Letters Patent, the toe-lasting machine herein shown is provided with a plurality of fluid-operated instrumentalities which operate on the shoe in the course of a cycle of power operations of the machine. As further disclosed especially in Letters Patent No. 2,391,461, granted on December 25, 1945, on an application of mine, the shoe is presented by the operator with the bottom of the forepart of the insole in engagement with a plate 2 (Fig. 1) provided with a spur 4 which enters an indentation previously formed in the insole to assist in positioning the shoe in proper relation to the lasting instrumentalities. Substantially at the beginning of the cycle of operations of the machine the shoe is clamped against the plate 2 by the upward movement of a toe rest 6. Included in the lasting instrumentalities are a toe former 8 which wipes the toe end of the upper heightwise of the last and a pair of wipers 10 which wipe the lasting margin of the toe end of the upper inwardly over an insole on the last. Prior to such operation of the wipers, however, the margin of all but the outer layer of the toe-end portion of the upper materials is trimmed off by trimming means identified generally by the reference character 12 (Fig. 4) and hot thermoplastic cement is applied to the toe end of the shoe for securing the margin of the upper to the insole, the cement-applying means being identified generally by the reference character 14. The trimming means and the cement-applying means are supported on a common carrier 16 which is mounted to swing about a vertical axis to carry the cement-applying means into position over the shoe after the operation of the trimming means thereon, such swinging movement of the carrier being effected by a piston 18 movable in a cylinder 20 to which operating fluid is admitted through a pipe line 22. After the margin of the upper has been wiped inwardly over the insole by the wipers 10 the machine comes automatically to a stop to cause the wipers to remain a few seconds in pressure-applying relation to the upper while the cement is setting. Thereafter the machine is again started and completes its cycle, releasing the shoe.

In addition to the piston 18 and the cylinder 20 associated with the carrier 16, there are provided other cylinder-and-piston devices for operating the toe rest 6, the toe former 8, the wipers 10, and other instrumentalities with which the machine is provided, the several devices being supplied with operating fluid, preferably oil,

under pressure from a manifold 24 (Fig. 14). Admission of the fluid to the different devices and exhaust of the fluid therefrom are controlled by valves, some of which are shown in Fig. 14. Among these valves, which are generally similar to one another in construction and manner of operation, is a valve 26 associated with the cylinder 20 and corresponding to the valve 713 shown in Letters Patent No. 2,324,509, this valve and its operating mechanism being shown in detail in Fig. 13. The valve is a sleeve valve mounted to slide on a tube 28 in communication at one end with the manifold 24 and at the other end with the pipe line 22, the tube having therein a partition 30 which divides one end portion thereof from the other. At one side of the partition are a plurality of ports 32 and at the other side thereof a plurality of ports 34. Formed in the valve is an annular chamber 36 through which the ports 32 are caused to communicate with the ports 34 to admit fluid from the manifold 24 to the pipe line 22 when the valve is moved toward the left from the position in which it is shown in Fig. 13. The valve is controlled through an arm 38 pivotally mounted at 40 on a bracket 42, a spring 44 being connected to this arm to maintain the valve normally in position to prevent communication between the manifold and the pipe line 22, as shown. The ports 34 are uncovered at that time to permit exhaust of fluid from the pipe line 22 back to a reservoir or sump 46. The arm 38 is swung into position to cause the valve to admit fluid to the pipe line by a lever 48 also pivoted at 40 on the bracket 42 and arranged thus to act on the arm 38 through a small compression spring 50 engaging a lug on the arm. The lever 48 is operated at the proper time in the cycle by one of a plurality of fingers 52 mounted on a rotatable drum 54 like that shown in Letters Patent No. 2,337,558, granted on December 28, 1943, on an application of mine, the finger being arranged to engage a roll 56 on one end of the lever. In this movement of the lever a latch 58 pivotally mounted thereon is carried into position to be swung by a spring 60 over a shoulder 62 on the bracket 42 to retain the valve 26 in the position to which it is moved, the spring 60 being connected to an arm 64 which is in fixed relation to the latch. At the proper time in the cycle another of the fingers 52 on the drum 54 acts on the arm 64 to swing the latch 58 from over the shoulder 62, whereupon the spring 44 returns the valve 26 to its initial position.

The drum 54 is rotated by fluid admitted to a cylinder 66 (Fig. 14) from the manifold 24 and acting on a piston 68 connected to the drum, the fluid being admitted to the cylinder by a valve 70 movable by the operator thus to start the cycle of operations of the machine. It will be understood that the cycle of operations corresponds to one complete rotation of the drum. Fluid is supplied to the manifold 24 from the sump 46 by a pump 72 driven continuously by an electric motor 74 and forcing the fluid into the manifold through a pipe line 76. When the machine is not in operation the fluid returns freely from the manifold to the sump through a valve 78 without developing any substantial pressure in the manifold. The valve 78 is moved by the operator to close the outlet from the manifold before the valve 70 is operated to start the machine, whereupon pressure is developed in the manifold and the excess fluid delivered by the pump returns to the sump 46 past a spring-controlled relief valve 80 which determines the pres-

sure in the manifold. At the end of the cycle of operations the valve 78 is returned automatically to its initial position to cause the pressure in the manifold to fall substantially to zero.

As thus far described the machine herein shown may be assumed to be constructed substantially as disclosed in the previously mentioned Letters Patent. As further disclosed in Letters Patent No. 2,420,665, granted on May 29, 1947, on an application of mine, it has attached to its right-hand side mechanism indicated generally by the reference character 82 (Fig. 1) for providing the insole with an indentation to receive the previously mentioned shoe-positioning spur 4, the shoe being presented to this mechanism before it is presented to the lasting instrumentalities. The indenting mechanism is operated by fluid delivered by the pump 12. In order to permit it to be thus operated when there is no pressure in the manifold 24, i. e., prior to the beginning of a cycle of operations of the lasting machine, there is provided an accumulator 84 (Fig. 14) comprising a cylinder 86 in which is a piston 88 movable against the resistance of a spring 90 by fluid admitted to the cylinder. Fluid is conducted to the accumulator from the pipe line 76 by a pipe line 92 in which is a check valve 94 to prevent return of the fluid. The fluid for operating the indenting mechanism is conducted to that mechanism from the accumulator through a pipe line 96. It will be understood that the accumulator is charged at any time when the manifold 24 contains fluid under pressure greater than that of the fluid in the accumulator, and that when the pressure in the manifold is reduced to zero at the end of each cycle of operations of the lasting machine the accumulator remains charged so that the indenting mechanism may be operated when the lasting machine is idle.

For purposes of this invention there is conveniently supported on the left-hand side of the frame of the lasting machine a toe-pressing and trimming attachment identified generally in Figs. 1 and 4 by the reference character 98. One of the functions of this attachment is to apply pressure to the cement-lasting marginal portion of the toe end of the upper immediately after removal of the shoe from the lasting instrumentalities to hold the upper on the insole until the cement has more firmly set, thus permitting the time during which the upper is held under pressure by the lasting wipers 10 to be shortened with a consequent increase in the output of the lasting machine. To this end, the attachment includes a presser consisting of a plate 100 (Figs. 8 and 10) arranged to engage the lasted marginal portion of the upper overlying the insole, the plate having therein a recess 102 so that it will extend inward only over the margin of the shoe bottom about the end and along the sides of the toe. The plate is flexible to permit it to bend and thus to conform to the contour of the shoe bottom for applying effective pressure to all portions of the upper beneath it. Beyond the end of the toe and also along the opposite side margins of the plate the latter is thickened, its side marginal portions being inserted in horizontal slots 104 (Fig. 11) formed in supporting members 106 which are fast on opposite side frame plates 108 of the attachment (Fig. 5). The plate 100 is held firmly in the slots 104 by a setscrew 110. The shoe is presented by the operator to receive the pressure of the plate by moving it lengthwise to a position where the marginal portion of the toe end

of the upper overlying the insole is under the plate. To guard against any damage to the shoe by contact with the front edge of the plate when it is thus presented, there are provided two tapered rolls 112 mounted to turn on studs 114 which are supported on the front ends of leaf springs 116 secured at their rear ends by screws 118 on the tops of the members 106, the rolls being arranged to engage respectively the opposite side portions of the shoe bottom. Initially the lower faces of the rolls are somewhat lower than the plate, as shown in Fig. 5, but after the shoe has been properly presented the leaf springs 116 are yieldable to permit the rolls to be lifted by the shoe when the shoe is forced upward against the plate. To position the shoe laterally in proper relation to the recess 102 in the plate 100, there are provided two leaf springs 120 arranged to extend rearwardly in converging relation to 15 each other to receive and to centralize the toe end of the shoe between them by their engagement with the sides of the toe. Each of these springs is secured against the inner vertical face of one of the members 106 by the flanged inner 20 end of a sleeve 122 (Fig. 8) which extends outwardly through a slot 124 formed in the member 106 and in the frame plate 108, a hand wheel 126 being threaded on this sleeve and engaging a washer 128 which bears on the frame plate. It 25 will thus be seen that by turning the hand wheel in one direction the spring 120 is clamped firmly against the member 106, and that upon turning the hand wheel reversely the spring is loosened to permit it to be adjusted in directions 30 lengthwise of the shoe by moving the sleeve 122 along the slot 124. Fast in the inner end portion of each sleeve 122 is a small sleeve 130 in which is threaded a screw 132 in engagement at its inner end with the corresponding spring 120. By 35 turning the two screws 132, therefore, the shoe-engaging portions of the springs 120 may be adjusted in directions widthwise of the shoe as may be required for shoes of different widths.

After the shoe has been presented as above described it is forced upwardly against the plate 100 by a shoe rest 134 engaging the top face of its toe-end portion. This shoe rest is supported on the upper end of a piston 136 (Figs. 5 and 6) movable vertically in a cylinder 138 which is part of a casting 140 (Fig. 7) secured to a horizontal frame plate 142. Springs 144 connected to pins 146 which extend from the piston through slots 148 in the cylinder 138 hold the piston initially in its lowest position determined by engagement 45 of the pins with the cylinder, the lower ends of the springs being connected to studs 150 threaded in the frame plate 142. Fluid is admitted to the lower end of the cylinder 138 and is later exhausted therefrom through a port 152 in the casting 140 under control of a horizontal slide valve 154 in the casting, this valve having an annular recess 156 in communication at all times with the port 152. When the valve is in its initial position, as shown in Fig. 7, this recess is in communication also with an exhaust port 158 from which a pipe 160 leads to a point over the sump 46 to permit return of the fluid to the sump. Operating fluid is admitted to the cylinder 138 to cause the shoe to be forced up against the plate 100 by movement of the valve 154 to a position in which an inlet port 162 in the casting 140, instead of the exhaust port 158, is in communication with the port 152. Since the cycle of operations of the lasting machine has been completed at the time when the shoe is forced up against

the plate 100, and since at that time there is no pressure in the manifold 24, as hereinbefore explained, fluid for operating the piston 136 is obtained from the accumulator 84 (Fig. 14). Accordingly, the inlet port 162 is in communication, 5 through a pipe 164, with the previously mentioned pipe line 92 through which the accumulator is charged by the pump 72.

The valve 154 is moved as above described into position to admit fluid to the cylinder 138 by electrical means. This includes a solenoid 166 having an armature 168 to which are pivotally connected the rear ends of two rods 170 extending forwardly at opposite sides respectively of the casting 140. At their front ends these rods extend through blocks 172 (Figs. 5 and 7) which are pivotally mounted on upwardly extending arms 174 of a forked lever 176 pivotally mounted at its lower end on the head of a stud 178 in the frame plate 142. This lever is connected between its upper and lower ends to the front end of the valve 154 by a pin 180 extending through slots 182 in the lever. The rods 170 also extend through openings in a plate 184 fast on the rear of the casting 140, and confined between this plate and collars 186 fast on the rods are springs 188. These springs, therefore, urge the rods in forward directions and by reason of the engagement of nuts 190 on the rods with the blocks 172 position the valve 154 initially as shown in Fig. 7, the limit of the movement of the valve by the springs being determined by a stop screw 192 in engagement with a lug 194 on the lever 176. When the electrical circuit of the solenoid 166 is closed the rods 170 are moved rearwardly against the resistance of the springs 188 and by reason of the engagement of the nuts 190 on the rods with the blocks 172 the valve is moved into position to admit the operating fluid to the cylinder 138.

The closing of the electrical circuit of the solenoid 166 to cause the valve 154 to be moved as above described is effected in response to the presentation of the shoe in position to be operated on. For this purpose there is slidingly mounted in a holder 198 (Figs. 6 and 10) a plunger 200 having on its front end a pad 202 arranged to be engaged by the toe-end face of the shoe when the shoe is presented. The holder 198 is secured to a switch box 204 which is fast on the frame. The plunger 200 is movable between limits determined by a pin 206 mounted therein and slots 208 in the holder 198 into which the pin extends. The plunger is urged in a forward direction by a spring 210 engaging a shoulder thereon. A reduced rearwardly extending portion of the plunger is in engagement with one end of a pin 212 the other end of which bears against a resiliently flexible member 214 carrying one of the contact elements of a switch 216 in the switch box 204. Accordingly, pressure of the toe-end face of the shoe against the pad 202 when the shoe is presented by the operator serves to close the switch 216 and thus to activate the solenoid 166, whereupon the fluid is admitted to the cylinder 138 and the shoe rest 134 is moved upwardly to force the shoe against the plate 100. It will be understood that the pad 202 serves further as an end gage for the shoe to determine its position lengthwise with respect to the recess 102 in the plate 100.

To assist in avoiding any possible lengthwise displacement of the shoe in a heelward direction by the pressure of the shoe rest 134 thereon, the lower face of the plate 100 is provided adjacent to the recess 102 with a series of fine corruga-

tions 218 (Fig. 8) which engage the upper. Further to insure against opening of the switch 216 in the event of any such slight displacement of the shoe, mechanism is provided for holding the switch closed independently of the shoe after it has been closed by the shoe. For this purpose there is pivotally mounted on a pin 220 in the holder 198 a bell-crank lever 222 on one arm of which is a finger 224 lying in a notch formed in the plunger 200. Pivots connected to the other arm of the bell-crank lever is a rod 226 extending downwardly through an opening in a member 228 threaded in the piston 136. Between this member and a collar 230 fast on the rod 226 is a compression spring 232. When the piston, therefore, is moved upwardly to cause the shoe against the plate 100 the spring 232 is compressed so that it acts through the bell-crank lever 222 on the plunger 200 to hold the switch 216 closed regardless of pressure of the toe end of the shoe on the pad 202.

After the lasting of the toe end of a shoe of the type herein shown a portion of the margin of the upper at a distance from the edge of the shoe bottom, especially near the end of the toe, usually projects more or less upwardly from the insole and needs to be trimmed off before an outsole is applied to the shoe. The pressing plate 100 is accordingly so formed and the shoe is so positioned that when such trimming is required the plate extends inwardly over the shoe bottom at the end of the toe a distance less than the width of the lasting margin of the upper, and mechanism is further provided for trimming off the surplus margin of the upper extending beyond the plate. This mechanism includes a trimming knife or cutter 234 mounted on a holder 236 which is supported by downwardly and forwardly extending arms 238 of two bell-crank levers 240 mounted to swing about a rod 242 supported by the frame plates 108 and extending widthwise of the shoe, the two bell-crank levers being rigidly connected together by a web 244. To operate the cutter 234 the bell-crank levers are swung in a clockwise direction with reference to Fig. 6 by means hereinafter described. The holder 236 is pivotally mounted on studs 246 (Fig. 5) on the ends of the arms 238 to swing relatively to the arms about an axis extending widthwise of the shoe and it is engaged by two spring-pressed plungers 248 carried by the arms 238, these plungers tending to swing it in a counterclockwise direction and holding it initially in contact with lugs 250 on the arms, as shown in Fig. 6. As the bell-crank levers 240 begin their operative swinging movement the cutter 234 has a substantial component of downward movement toward the plate 100, after which it is moved bodily lengthwise of the shoe along the plate toward the end of the toe to trim off the surplus margin of the upper, as illustrated in Fig. 10. To prevent the edge of the cutter from engaging the plate when the cutter is thus moved downwardly there are fast on the holder 236 two fingers 252 (Figs. 5 and 9) which engage the plate ahead of the cutter and cause the holder to swing about the studs 246 against the resistance of the plungers 248 until the cutter is more nearly parallel to the shoe bottom, after which the cutter itself engages the top of the plate and is held yieldingly in contact with it by the plungers, irrespective of the earlier bending of the plate, in the upper-trimming operation. It will be understood that in this operation the plate holds portions of the upper

adjacent to the line of the cut against the thrust of the cutter.

For swinging the bell-crank levers 240 to operate the cutter in the manner above described rearwardly extending arms 254 of these levers are connected by links 256 to a crossbar 258 (Figs. 5 and 6) fast on the upper end of a piston 260 vertically movable in a cylinder 262 fast on the frame plate 142. Springs 264 connected to the crossbar and to studs 266 in the plate 142 tend to move the piston downwardly and hold the bell-crank levers 240 normally in their initial positions determined by engagement of a pin 268 in the piston with the cylinder 262 at the lower ends of slots 270 in the cylinder. The limit of the upward movement of the piston and of the operative movement of the cutter is further determined by engagement of the pin with the cylinder at the upper ends of the slots. Conveniently the piston 260 is operated at a predetermined time in the next cycle of operations of the lasting machine after the previously lasted shoe has been clamped against the plate 100 by the toe rest 134, and for this purpose operating fluid is conducted to the cylinder 262 by a pipe 272 (Figs. 4 and 14) leading from the previously mentioned pipe line 22 to which fluid is admitted by the valve 26 for swinging the carrier 16 to bring the cement-applying means 14 into position over the shoe after the trimming of the inner layers of the upper materials by the trimming means 12. After the cutter 234 has been operated it remains at the limit of its operative movement until, in the course of the cycle of operations of the lasting machine, the valve 26 is returned into position to release the fluid from the pipe line 22, whereupon the piston 260 is moved downwardly by the springs 264 and the cutter is thereby returned to its initial position.

The cutter 234 is inserted in the holder 236 by sliding it into grooves 274 (Fig. 5) formed in the holder. Its position with respect to the holder is determined by a screw 276 (Fig. 10) which is threaded in the holder and is provided with a flange 278 extending into a groove in the cutter. By means of this screw the cutter may be adjusted along the grooves to vary the position of its cutting edge relatively to the previously mentioned fingers 252 (Fig. 5).

To dispose of the waste material received from the upper by the cutter 234 there is provided an ejector 280 (Fig. 10). As shown further in Fig. 9, this ejector includes an inclined plate 282 positioned normally with its lower edge in engagement with the top of the cutter 234 in a recess in the holder 236. Extending from this plate is an arm 284 pivotally mounted on a pin 286 carried by an arm 288 which is mounted to swing about the previously mentioned rod 242 between the bell-crank levers 240. A spring-pressed plunger 290 in the arm 288 engages the arm 284 and holds the plate 282 down on the cutter 234. The arm 288 is connected by a link 292 to one arm 294 of a bell-crank lever 296 mounted to swing about a rod 298 which provides the connection between the arms 254 and the links 256. A spring 300 connected to the arm 294 and to a pin 302 in the web 244 holds the arm 288 initially in a position determined by the engagement of a screw 304 mounted in a lug 306 on the hub of the arm with the web 244. By the cutter-operating movement of the bell-crank levers 240 the bell-crank lever 296 is carried upwardly to a position where an arm 308 thereof extends over the upper end of a pawl 310 pivotally mounted

on a pin 312 which is supported by a block 314 fast on the frame. A spring-pressed pin 316 in the block holds the pawl normally in a position determined by engagement of a tail portion 318 thereof with a screw 320 in the block. Accordingly, in response to the return movement of the bell-crank levers 240 after the trimming operation the bell-crank lever 296 is swung by the pawl 310 in a clockwise direction (Fig. 12) and thereby 5 swings the arm 288 to carry the plate 282 rearwardly from over the cutter 234 and along the top of the plate 100 to move the waste material into a trough 322 (Fig. 8) arranged to receive it. This trough includes a horizontal plate 324 secured to the frame plates 108 in the same plane 10 as the presser plate 100, and upstanding side plates 326 the front end portions of which are curved outwardly away from each other and extend over the presser plate 100. Preferably the trough 322 extends rearwardly and downwardly 20 to a position over the top of a receptacle (not shown) with which the machine is provided to receive the waste material removed from the upper by the trimming means 12 (Fig. 4), as disclosed in Letters Patent No. 2,324,509. It will be understood that successive increments of waste material in the trough 322 are pushed along the trough toward the receptacle by the ejector 280. It will further be understood that in the course 25 of the return movement of the bell-crank levers 240 after the trimming operation the arm 308 of the bell-crank lever 296 slips off the end of the pawl 310, whereupon the spring 300 returns the arm 288 and the plate 282 to the positions determined by engagement of the screw 304 with the web 244.

The shoe is released by the shoe rest 134 near the end of the cycle of operations of the lasting machine. For this purpose there is fast on the 40 drum 54 a ring 328 (Figs. 2 and 3) carrying a screw 330 the head of which is arranged to engage a lever 332 pivotally mounted at 334 on a bracket 336 fast on the frame of the machine, the bracket supporting a switch box 337. The lever 332 engages a plunger 338 movable in the switch box and bearing against a resiliently flexible member 340 which carries one of the contact elements of a switch 342 in the circuit of the solenoid 166. The switch is operated to break the circuit by the action of a screw 330 on the lever 332, whereupon the valve 154 (Fig. 7) is returned to exhaust position by the springs 188 and the shoe rest is moved downwardly by the springs 144, releasing the shoe. Prior to the 45 end of the cycle the screw 330 releases the lever 332 the return movement of which is limited by engagement of a screw 343 in its lower end with the switch box. This causes the switch 342 again to close, but at that time the switch 216 (Fig. 6) is open by reason of the release of the shoe and the return of the piston 136. When the shoe is thus released and falls it is caught and held by a shoe receiver 344 comprising a pair of downwardly inclined rods 346 secured at their upper ends to the frame plates 108, the rods having thereon diverging wings 348 between which the shoe is received and being provided at their lower ends with a pad 350 for engaging the heel-end face of the shoe.

To avoid the necessity of running the lasting machine idly through a cycle of operations in order to cause the cutter 234 to operate on the last shoe, there is provided means whereby the operator may move the valve 26 (Fig. 13) manually to admit fluid from the manifold 24 to the

11

pipe line 22. This means comprises a wire 352 guided by a flexible cable 354 and connected at one end to the valve-operating lever 48, the other end of the wire being connected to a pin 356 slidingly movable in a front frame plate 358 and having fast on its outer end a knob 360. A spring 362 mounted between the frame plate and a member 364 fast on the pin 356 holds the knob 360 normally against the front of the frame plate. To cause the cutter 234 to operate on the last shoe the operator pulls on the wire 352 by means of the knob 360, thus moving the valve 26 into position to admit fluid to the pipe line 22. The member 364 is so adjusted on the pin 356 that by engagement with the frame plate 358 it prevents the lever 48 from being moved far enough to cause the latch 58 to swing inwardly over the shoulder 62. After the operation of the cutter the operator releases the knob 360, whereupon the valve 26 is returned to its initial position and releases the fluid from the pipe line 22 to cause return movement of the cutter. It will be understood that the movement of the valve 26 results also in an idle swinging movement of the carrier 16 (Fig. 4). Since the pressure in the manifold 24 falls substantially to zero upon the completion of each cycle of operations of the lasting machine, the operator, before operating the valve 26 as above described, moves the valve 18 (Fig. 14) into position to close the outlet from the manifold and thus to cause the development of pressure therein as he normally does prior to starting each cycle of operations. After the operation of the cutter and the return of the valve 26 to its initial position the operator causes the valve 18 to return and to release the fluid from the manifold by movement of a member not herein shown with which the machine is provided, this member being that identified by the reference character 1214 in Letters Patent No. 2,324,509. In order to cause the release of the last shoe after it has been trimmed the operator breaks the circuit of the solenoid 166 by a hand switch (not shown) mounted in a switch box 366 (Fig. 5) and controlled by a handle 368.

The operations hereinbefore described, in so far as they are of special interest with reference to the present invention, will now be briefly summarized. It will be understood that in the course of the cycle of operations of the lasting machine the toe end of the shoe is lasted in the same manner as heretofore, except that the wipers 10, after wiping the margin of the upper inwardly over the insole, remain for only a comparatively brief time in pressure-applying relation to the upper. Immediately upon release of the shoe at the end of the cycle the operator presents it to the pressing and trimming attachment 98, moving it lengthwise under the guidance of the rolls 112 into position beneath the pressing plate 100 until its toe-end face presses against the pad 202. The pressure of the shoe on this pad operates the switch 216 (Fig. 6) to close the electrical circuit of the solenoid 166, thus causing the valve 154 to be moved into position to admit operating fluid from the accumulator 84 to the cylinder 138. By the fluid thus admitted to the cylinder the shoe rest 134 is moved upwardly to force the shoe firmly against the plate 100, the latter bending more or less to conform to the contour of the shoe bottom. In this operation the spring 232 is compressed to insure that the switch 216 will remain closed. The operator then presents the next shoe to the lasting instrumentalities and again starts the cycle of operations of the lasting machine. At

12

the time in that cycle when the valve 26 is operated to admit fluid to the pipe line 22 and thus to cause the carrier 16 (Fig. 4) to be swung into position to bring the cement-applying means 14 over the shoe, fluid from the same pipe line 22 is admitted to the cylinder 262 to operate the cutter 234. As the cutter is operated through the bell-crank lever 240 it receives first a component of downward movement toward the plate 100, the members 252 (Figs. 5 and 9) engaging this plate and causing the cutter holder 236 to swing about the studs 246 on the arms 238. In this manner the cutter is caused to assume a position more nearly parallel to the plate 100, and as it is moved farther lengthwise of the shoe toward the end of the toe its cutting edge engages the top of the plate and trims off the surplus margin of the upper extending inwardly and upwardly beyond the plate (Fig. 10), the operative movement of the cutter being limited by engagement of the pin 268 with the cylinder 262 at the upper ends of the slots 270. Near the end of the operative movement of the cutter the arm 308 of the bell-crank lever 296 is carried upwardly past the yielding pawl 310 and the pawl snaps inwardly under the arm. At the time in the cycle of operations of the lasting machine when the fluid is released from the pipe line 22 by return movement of the valve 26 the bell-crank levers 240 are returned by the springs 264 acting on the piston 260. Early in this return movement of the bell-crank levers and the cutter the pawl 310 causes the bell-crank lever 296 to swing in the direction to operate the ejector 280 (Fig. 12), thus causing the ejector to force the waste material removed from the upper over the plate 100 and into the trough 322 by which the successive increments of waste material removed from the different shoes are conducted to a waste receptacle (not shown). As the bell-crank levers 240 continue their return movement the arm 308 slips off the pawl 310, whereupon the spring 300 returns the ejector 280 to its initial position with respect to the cutter holder 236. Near the end of the cycle of operations of the lasting machine the screw 330 (Fig. 3) acts on the lever 332 to open the switch 342, thus breaking the electrical circuit of the solenoid 166 and causing the valve 154 to return to its initial position and to release the fluid from the cylinder 138. The shoe rest 134 is then returned by the springs 144, thereby releasing the shoe which falls and is caught and held by the shoe receiver 344. Just before the completion of the cycle of the lasting machine the screw 330 passes beyond the lever 332, causing the switch 342 again to close, the switch 216 being then open. Accordingly the pressing and trimming attachment is in condition to receive the next shoe immediately upon its release by the lasting machine. To cause the cutter 234 to operate on the last shoe when the lasting machine is idle, the operator manipulates the valve 26 by means of the wire 352 (Fig. 13), after he has closed the valve 18 to cause pressure to develop in the manifold 24, and after the operation of the cutter he again opens the valve 18. To cause the shoe rest 134 to release the last shoe he breaks the circuit of the solenoid 166 by means of the handle 368 (Fig. 5) on the switch box 366. It will be understood that although the shoe remains under the pressure of the lasting wipers a substantially shorter time than heretofore, the lasted margin of the upper is held effectively enough in lasted position by the cement in the brief interval before it is subjected to the further

pressure of the pressing plate 100. It will be evident that the margin of the upper is normally held by this plate until the next shoe is presented to the lasting machine and substantially throughout the next cycle of operations of the machine, during which time the setting of the cement is completed to cause it to hold the upper securely.

Having described the invention, what I claim as new and desire to secure by Letters Patent of the United States is:

1. In a machine for operating on shoes, a presser constructed and arranged to engage the upper on the bottom of the toe-end portion of a shoe presented thereto after the toe-lasting operation, said presser being formed to extend inwardly over the marginal portion only of the shoe bottom about the end and along the sides of the toe and being flexible to permit it to conform to the contour of the shoe bottom, means for positioning the shoe relatively to the presser, a shoe rest arranged to engage the top the forepart of the shoe, means supporting said presser and shoe rest in predetermined relation to each other to receive the shoe supported by the operator with the upper on the margin of the shoe bottom facing the presser, and means for effecting relative movement of said presser and shoe rest while the operator thus supports the shoe to cause the presser to press the upper on the shoe bottom.

2. In a machine for operating on shoes, a presser for engaging the upper on the bottom of the toe-end portion of a shoe presented thereto after the toe-lasting operation, said presser comprising a plate formed to extend inwardly over the marginal portion only of the shoe bottom about the end and along the sides of the toe, the plate being flexible to permit it to conform to the contour of the shoe bottom and being arranged to receive a shoe supported by the operator underneath it, a shoe rest for engaging the top of the forepart of the shoe, and power-operated means for moving said shoe rest upwardly while the operator thus supports the shoe to force the shoe against said plate.

3. In a machine for operating on shoes, a presser for engaging the upper on the bottom of the toe-end portion of a shoe presented thereto after the toe-lasting operation, said presser being formed to extend inwardly over the marginal portion only of the shoe bottom about the end and along the sides of the toe and being arranged to receive the shoe presented initially underneath it, means for positioning the shoe relatively to the presser by engagement with the upper on the end and side faces of the toe, a shoe rest for engaging the top of the forepart of the shoe, and means for moving said shoe rest upwardly to force the shoe against the presser.

4. In a machine for operating on shoes, a presser for engaging the upper on the bottom of the toe-end portion of a shoe presented thereto after the toe-lasting operation, said presser being arranged to receive a shoe supported by the operator underneath it, a shoe rest for engaging the top of the forepart of the shoe, and power-operated means for moving said shoe rest upwardly while the operator thus supports the shoe to force the shoe against said presser.

5. In a machine for operating on shoes, a presser constructed and arranged to engage the upper on the bottom of the toe-end portion of a shoe presented thereto after the toe-lasting operation, said presser being formed to extend in-

wardly over the marginal portion only of the shoe bottom about the end and along the sides of the toe, means for positioning the shoe relatively to the presser comprising a pair of leaf springs arranged to extend lengthwise along the sides of the shoe in converging relation for yielding engagement with the upper at the opposite sides of the toe respectively, and means for effecting relative movement of said presser and the shoe thus positioned to cause the presser to press the upper on the shoe bottom.

6. In a machine for operating on shoes, a presser constructed and arranged to engage the upper on the bottom of the toe-end portion of a shoe presented thereto after the toe-lasting operation, said presser being formed to extend inwardly over the marginal portion only of the shoe bottom about the end and along the sides of the toe, means for positioning the shoe relatively to the presser comprising a pair of leaf springs arranged to extend lengthwise along the sides of the shoe for yielding engagement with the upper at the opposite sides of the toe respectively, means for adjusting said springs by flexing them laterally of the shoe, and means for effecting relative movement of the presser and the shoe thus positioned to cause the presser to press the upper on the shoe bottom.

7. In a machine for operating on shoes, a presser for engaging the upper on the bottom of the toe-end portion of a shoe presented thereto after the toe-lasting operation, means arranged for rolling contact with the bottom of the shoe to guide the shoe for lengthwise movement to a position where the upper on the toe end of the shoe bottom faces the presser, and means for effecting relative movement of the shoe and the presser to cause the presser to press the upper on the shoe bottom.

8. In a machine for operating on shoes, a presser for engaging the upper on the bottom of the toe-end portion of a shoe presented thereto after the toe-lasting operation, a pair of rolls arranged to engage the opposite side portions of the bottom of the shoe respectively to guide the shoe for lengthwise movement to a position where the upper on the toe end of the shoe bottom faces the presser, and means for effecting relative movement of the shoe and the presser to cause the presser to press the upper on the shoe bottom.

9. In a machine for operating on shoes, a presser for engaging the upper on the bottom of the toe-end portion of a shoe presented thereto after the toe-lasting operation, a pair of rolls arranged to engage the opposite side portions of the bottom of the shoe respectively to guide the shoe for lengthwise movement to a position where the upper on the toe end of the shoe bottom faces the presser, said rolls being yieldingly movable heightwise of the shoe in response to pressure of the shoe thereon, and means for effecting relative movement of the shoe and the presser to cause the presser to press the upper on the shoe bottom.

10. In a machine for operating on shoes, a presser for engaging the upper on the bottom of the toe-end portion of a shoe presented thereto after the toe-lasting operation, said presser being so formed as to extend inwardly over the marginal portion only of the shoe bottom about the end and along the sides of the toe, a pair of rolls arranged to engage the opposite side portions of the shoe bottom respectively to guide the shoe for lengthwise movement to a position where the

15

upper on the toe end of the shoe bottom faces the presser, a pair of leaf springs arranged to extend lengthwise along the sides of the shoe toward the end of the toe in converging relation for yielding engagement with the upper on the opposite sides of the toe to position the shoe laterally when it is thus presented; an end gage for determining the position of the shoe lengthwise by engagement with its toe-end face, and means for effecting relative movement of the presser and the shoe thus positioned to cause the presser to press the upper on the shoe bottom.

11. In a machine for operating on shoes, the combination with a device for performing an operation on the toe end of a shoe, of means for positioning the shoe relatively to said device comprising a pair of separate leaf springs arranged to extend lengthwise along the sides of the shoe toward the end of the toe in such converging relation as to be forced apart by engagement of the upper therewith at the opposite sides of the toe respectively as the shoe is moved lengthwise between them.

12. In a machine for operating on shoes, the combination with means for performing an operation on a shoe, of a pair of rolls arranged to engage the opposite side portions of the bottom of the shoe respectively to guide the shoe for lengthwise movement into position to be thus operated on, said rolls being yieldingly movable in a direction heightwise of the shoe in response to pressure of the shoe thereon.

13. In a machine for operating on shoes, a presser constructed and arranged to engage the upper on the bottom of the toe-end portion of a shoe presented thereto by the operator after the toe-lasting operation, a shoe rest arranged to engage the top of the forepart of the shoe, and power-operated means controlled by the shoe for effecting relative movement of said presser and shoe rest to cause the presser to press the upper on the shoe bottom in response to the presentation of the shoe thereto.

14. In a machine for operating on shoes, a presser constructed and arranged to engage the upper on the bottom of the toe-end portion of a shoe presented thereto by the operator after the toe-lasting operation, a shoe rest arranged to engage the top of the forepart of the shoe, power-operated means for effecting relative movement of said presser and shoe rest to cause the presser to press the upper on the shoe bottom, and electrical means controlled by the shoe for rendering said power-operated means thus operative in response to the presentation of the shoe.

15. In a machine for operating on shoes, a presser constructed and arranged to engage the upper on the bottom of the toe-end portion of a shoe presented thereto by the operator after the toe-lasting operation, a shoe rest arranged to engage the top of the forepart of the shoe, fluid-operated means for moving said shoe rest heightwise of the shoe to force the shoe against the presser and thus to cause the presser to press the upper on the shoe bottom, a member arranged to be engaged by the toe-end face of the shoe when it is presented, and electrical means controlled by said member for admitting operating fluid to said fluid-operated means in response to the presentation of the shoe.

16. In a machine for operating on shoes, a presser constructed and arranged to engage the upper on the bottom of the toe-end portion of a shoe presented thereto by the operator after the toe-lasting operation, a shoe rest arranged to en-

16

gage the top of the forepart of the shoe, power-operated means for effecting relative movement of said presser and shoe rest to cause the presser to press the upper on the shoe bottom, a member arranged to be engaged by the toe-end face of the shoe, electrical means including a switch arranged to be closed by pressure of the shoe on said member to render said power-operated means thus operative, and mechanism movable by said power-operated means to insure against opening of said switch in the event of any lengthwise displacement of the shoe when the pressure is applied thereto.

17. In a machine for operating on shoes, a presser constructed and arranged to engage the upper on the bottom of the toe-end portion of a shoe presented thereto by the operator after the toe-lasting operation, a shoe rest arranged to engage the top of the forepart of the shoe, power-operated means for effecting relative movement of said presser and shoe rest to cause the presser to press the upper on the shoe bottom, a member arranged to be engaged by the toe-end face of the shoe, electrical means including a switch arranged to be closed by pressure of the shoe on said member to render said power-operated means thus operative, and mechanism movable by said power-operated means to apply closing force to said switch independently of the shoe and thus to prevent opening of the switch in the event of any lengthwise displacement of the shoe when the pressure is applied thereto.

18. In a machine for operating on shoes, power-operated means for performing an operation on a shoe, a member arranged to be engaged by the shoe, electrical means including a switch arranged to be closed by pressure of the shoe on said member to render said power-operated means thus operative, and additional power-operated means for insuring independently of the shoe against opening of said switch when the shoe is thus operated on.

19. In a machine for operating on shoes, power-operated means for performing an operation on a shoe, a member arranged to be engaged by the shoe, electrical means including a switch arranged to be closed by pressure of the shoe on said member to render said power-operated means thus operative, and automatic means for applying closing force to said switch independently of the shoe to insure against opening of the switch when the shoe is thus operated on.

20. In a machine for operating on shoes, means for lasting the toe-end portion of a shoe in a cycle of automatic operations of the machine, pressing means arranged to receive the shoe after the toe-lasting operation and to apply pressure to the margin of the toe end of the upper on the shoe bottom independently of a cycle of operations of the machine, and automatic means for effecting the release of the shoe from said pressing means by the next cycle of operations of the machine.

21. In a machine for operating on shoes, means for lasting the toe-end portion of a shoe in a cycle of automatic operations of the machine, pressing means arranged to receive the shoe after the toe-lasting operation and to apply pressure to the margin of the toe end of the upper on the shoe bottom independently of a cycle of operations of the machine, electrical means including a solenoid for rendering said pressing means thus effective on the shoe only as long as the solenoid is energized, and automatic means for breaking the electrical circuit of the solenoid by the next cycle

of operations of the machine to effect the release of the shoe from the pressing means.

22. In a machine for operating on shoes, means for lasting the toe-end portion of a shoe in a cycle of automatic operations of the machine, a presser for thereafter pressing the margin of the toe end of the upper on the shoe bottom independently of a cycle of operations of the machine, a shoe rest for forcing the shoe against said presser, means for thus operating said shoe rest in response to presentation of the shoe to the presser, and automatic means for causing the shoe rest to release the shoe by the next cycle of operations of the machine.

23. In a machine for operating on shoes, means for lasting the toe-end portion of a shoe in a cycle of automatic operations of the machine, a presser for thereafter pressing the margin of the toe end of the upper on the shoe bottom independently of a cycle of operations of the machine, a shoe rest movable to force the shoe against said presser, fluid-operated means for thus moving said shoe rest, electrical means including a solenoid for rendering said fluid-operated means thus operative in response to presentation of the shoe to the presser and for maintaining it effective on the shoe rest only as long as the solenoid is energized, and automatic means for breaking the electrical circuit of the solenoid by the next cycle of operations of the machine to cause the release of the shoe by the shoe rest.

24. In a machine for operating on shoes, a presser for engaging the upper on the bottom of the toe-end portion of a shoe presented thereto after the toe-lasting operation, said presser being constructed and arranged to extend inwardly over the shoe bottom at the end of the toe a distance less than the width of the lasting margin of the upper, a shoe rest arranged to engage the top of the forepart of the shoe, means supporting said presser and shoe rest in predetermined relation to each other to receive the shoe presented initially with the upper on the margin of the shoe bottom facing the presser, means for effecting relative movement of said presser and shoe rest to clamp and hold the shoe between them, and a cutter movable to trim off at the toe surplus marginal upper material extending beyond the presser while the shoe is so held.

25. In a machine for operating on shoes, a presser for engaging the upper on the bottom of the toe-end portion of a shoe presented thereto after the toe-lasting operation, said presser being constructed and arranged to extend inwardly over the shoe bottom at the end of the toe a distance less than the width of the lasting margin of the upper, a shoe rest arranged to engage the top of the forepart of the shoe, means supporting said presser and shoe rest in predetermined relation to each other to receive the shoe presented initially with the upper on the margin of the shoe bottom facing the presser, means for effecting relative movement of said presser and shoe rest to clamp and hold the shoe between them, and a cutter movable bodily lengthwise of the shoe along the shoe bottom toward the end of the toe to trim off surplus marginal upper material extending beyond the presser while adjacent portions of the upper are held by the presser against the thrust of the cutter.

26. In a machine for operating on shoes, a presser for engaging the upper on the bottom of the toe-end portion of a shoe presented thereto after the toe-lasting operation, said presser being constructed and arranged to extend inwardly over

the shoe bottom at the end of the toe a distance less than the width of the lasting margin of the upper and being flexible to permit it to conform to the contour of the shoe bottom, a shoe rest arranged to engage the top of the forepart of the shoe, means supporting said presser and shoe rest in predetermined relation to each other to receive the shoe presented initially with the upper on the margin of the shoe bottom facing the presser, means for effecting relative movement of said presser and shoe rest to clamp and hold the shoe between them, and a cutter movable along said flexible presser in contact therewith to trim off surplus marginal upper material extending beyond the presser while the shoe is so held.

27. In a machine for operating on shoes, a presser for engaging the upper on the bottom of the toe-end portion of a shoe presented thereto after the toe-lasting operation, said presser being constructed and arranged to extend inwardly over the shoe bottom at the end of the toe a distance less than the width of the lasting margin of the upper, a shoe rest arranged to engage the top of the forepart of the shoe, means supporting said presser and shoe rest in predetermined relation to each other to receive the shoe presented initially with the upper on the margin of the shoe bottom facing the presser, means for effecting relative movement of said presser and shoe rest to clamp and hold the shoe between them, a cutter movable along said presser to trim off surplus marginal upper material extending beyond the presser while the shoe is so held, and means for yieldingly urging said cutter heightwise of the shoe toward the presser in the upper-trimming operation.

28. In a machine for operating on shoes, a presser for engaging the upper on the bottom of the toe-end portion of a shoe presented thereto after the toe-lasting operation, said presser being constructed and arranged to extend inwardly over the shoe bottom at the end of the toe a distance less than the width of the lasting margin of the upper, a shoe rest arranged to engage the top of the forepart of the shoe, means supporting said presser and shoe rest in predetermined relation to each other to receive the shoe presented initially with the upper on the margin of the shoe bottom facing the presser, means for effecting relative movement of said presser and shoe rest to clamp and hold the shoe between them, a cutter for trimming off at the toe surplus marginal upper material extending beyond the presser while the shoe is so held, and a support for said cutter movable about an axis extending widthwise of the shoe to impart to the cutter bodily movement lengthwise of the shoe along the shoe bottom toward the end of the toe thus to trim the upper, said support being thereafter reversely movable to return the cutter.

29. In a machine for operating on shoes, a presser constructed and arranged to engage the upper on the bottom of the lasted toe-end portion of a shoe but to extend inwardly over the shoe bottom at the end of the toe a distance less than the width of the lasting margin of the upper, said presser being flexible to permit it to bend and thus to conform to the contour of the shoe bottom, and a cutter movable along the shoe bottom in engagement with said presser irrespective of the bending thereof to trim off surplus marginal upper material extending beyond the presser.

30. In a machine for operating on shoes, a presser constructed and arranged to engage the upper on the bottom of the lasted toe-end por-

tion of a shoe but to extend inwardly over the shoe bottom at the end of the toe a distance less than the width of the lasting margin of the upper, a cutter movable lengthwise of the shoe along the shoe bottom toward the end of the toe to trim off surplus marginal upper material extending beyond the presser, and means for yieldingly urging said cutter heightwise of the shoe toward the presser in the upper-trimming operation.

31. In a machine for operating on shoes, a presser constructed and arranged to engage the upper on the bottom of the lasted toe-end portion of a shoe but to extend inwardly over the shoe bottom at the end of the toe a distance less than the width of the lasting margin of the upper, said presser being flexible to permit it to conform to the contour of the shoe bottom, a cutter movable lengthwise of the shoe along the shoe bottom toward the end of the toe to trim off surplus marginal upper material extending beyond the presser, and means for yieldingly urging said cutter heightwise of the shoe toward the presser to maintain it in contact therewith in the upper-trimming operation.

32. In a machine for operating on shoes, a presser constructed and arranged to engage the upper on the bottom of the lasted toe-end portion of a shoe but to extend inwardly over the shoe bottom at the end of the toe a distance less than the width of the lasting margin of the upper, a cutter for trimming off at the toe surplus marginal upper material extending beyond the presser, and a support for said cutter movable about an axis extending widthwise of the shoe to impart to the cutter bodily movement lengthwise of the shoe along the shoe bottom toward the end of the toe thus to trim the upper, said support being thereafter reversely movable to return the cutter.

33. In a machine for operating on shoes, a presser constructed and arranged to engage the upper on the bottom of the lasted toe-end portion of a shoe but to extend inwardly over the shoe bottom at the end of the toe a distance less than the width of the lasting margin of the upper, a cutter for trimming off at the toe surplus marginal upper material extending beyond the presser, a support for said cutter movable to carry the cutter bodily lengthwise of the shoe along the shoe bottom toward the end of the toe thus to trim the upper, a holder for said cutter movable mounted on said support, and spring means arranged to act on said holder to maintain the cutter yieldingly in contact with the presser in the upper-trimming operation.

34. In a machine for operating on shoes, a presser constructed and arranged to engage the upper on the bottom of the lasted toe-end portion of a shoe but to extend inwardly over the shoe bottom at the end of the toe a distance less than the width of the lasting margin of the upper, a cutter for trimming off at the toe surplus marginal upper material extending beyond the presser, a support for said cutter movable about an axis extending widthwise of the shoe to impart to the cutter bodily movement lengthwise of the shoe along the shoe bottom toward the end of the toe thus to trim the upper, a holder for the cutter mounted on said support for swinging movement heightwise of the shoe about an axis extending widthwise of the shoe, and spring means arranged to act on said holder to urge the cutter heightwise of the shoe toward the presser in the upper-trimming operation.

35. In a machine for operating on shoes, a

presser constructed and arranged to engage the upper on the bottom of the lasted toe-end portion of a shoe but to extend inwardly over the shoe bottom at the end of the toe a distance less than the width of the lasting margin of the upper, a cutter for trimming off at the toe surplus marginal upper material extending beyond the presser, a support for said cutter movable about an axis extending widthwise of the shoe to carry the cutter heightwise of the shoe toward the presser and then lengthwise of the shoe along the shoe bottom toward the end of the toe thus to trim the upper, a holder for the cutter mounted on said support for swinging movement heightwise of the shoe about an axis extending widthwise of the shoe, spring means arranged to act on said holder to urge the cutter heightwise of the shoe toward the presser and to maintain the cutter in contact with the presser in the upper-trimming operation, and means on said holder for engaging the presser to prevent contact of the cutter with the presser until after said support has received a portion of its swinging movement.

36. In a machine for operating on shoes, a cutter movable relatively to a shoe to trim off the surplus margin of the toe end of the upper, means for moving said cutter bodily thus to trim the upper, an ejector for engaging the waste material removed from the upper, and means for moving said ejector relatively to the cutter in the same direction as the trimming movement of the cutter to eject the waste material.

37. In a machine for operating on shoes, a cutter movable relatively to a shoe to trim off the surplus margin of the toe end of the upper, means for moving said cutter bodily thus to trim the upper, an ejector for engaging the waste material removed from the upper, and means for moving said ejector with the cutter in the upper-trimming operation and for thereafter moving it farther in the same direction relatively to the cutter to eject the waste material.

38. In a machine for operating on shoes, an upper-trimming cutter, a support for said cutter movable about an axis extending widthwise of a shoe to cause the cutter to trim off the surplus margin of the toe end of the upper, an ejector for engaging the waste material removed from the upper, and a support for said ejector movable about the same axis as said cutter support to cause the ejector to eject the waste material.

39. In a machine for operating on shoes, a cutter movable relatively to a shoe to trim off the surplus margin of the toe end of the upper, means for moving said cutter bodily thus to trim the upper and for thereafter moving it reversely to starting position, an ejector for engaging the waste material removed from the upper, and means for moving said ejector in the same direction as the trimming movement of the cutter to eject the waste material in the course of the reverse movement of the cutter.

40. In a machine for operating on shoes, an upper-trimming cutter, a support for said cutter movable relatively to a shoe to cause the cutter to trim off the surplus margin of the toe end of the upper and thereafter reversely movable to starting position, an ejector for engaging the waste material removed from the upper, and mechanism for moving said ejector away from the cutter to eject the waste material in response to the reverse movement of said cutter support.

41. In a machine for operating on shoes, an upper-trimming cutter, a support for said cutter

movable to carry the cutter bodily lengthwise of a shoe to cause it to trim off the surplus margin of the toe end of the upper and thereafter reversely movable to starting position, an ejector for engaging the waste material removed from the upper, and mechanism connected to said ejector for moving it in the same direction as the bodily trimming movement of the cutter to eject the waste material in response to the reverse movement of said cutter support.

42. In a machine for operating on shoes, an upper-trimming cutter, a support for said cutter movable relatively to a shoe to cause the cutter to trim off the surplus margin of the toe end of the upper and thereafter reversely movable to starting position, an ejector for engaging the waste material removed from the upper, mechanism connected to said ejector and movable with the cutter support in the upper-trimming operation, and means for operating said mechanism to move the ejector away from the cutter in the same direction as the trimming movement of the cutter to eject the waste material in response to the reverse movement of said cutter support.

43. In a machine for operating on shoes, an upper-trimming cutter, a support for said cutter movable relatively to a shoe to cause the cutter to trim off the surplus margin of the toe end of the upper and thereafter reversely movable to starting position, an ejector for engaging the waste material removed from the upper, mechanism connected to said ejector and movable with the cutter support in the upper-trimming operation, and a device into operative relation to which said mechanism is thus movable for causing it to operate the ejector to eject the waste material in response to the reverse movement of the cutter support.

44. In a machine for operating on shoes, an upper-trimming cutter, a support for said cutter movable relatively to a shoe to cause the cutter to trim off the surplus margin of the toe end of the upper and thereafter reversely movable to starting position, an ejector movable with the cutter for engaging the waste material removed from the upper, mechanism connected to said ejector and movable with the cutter support in the upper-trimming operation, means for operating said mechanism in response to the reverse movement of the cutter support to cause the ejector to eject the waste material and for then releasing the mechanism, and spring means for returning the ejector to its initial position relatively to the cutter when the mechanism is thus released.

45. In a machine for operating on shoes, an upper-trimming cutter, a support for said cutter movable about an axis extending widthwise of a shoe to cause the cutter to trim off the surplus margin of the toe end of the upper and thereafter reversely movable to starting position, an ejector for engaging the waste material removed from the upper, a support for said ejector movable about the same axis as said cutter support, and means for thus moving said ejector support to cause the ejector to eject the waste material in response to the reverse movement of the cutter support.

46. In a machine for operating on shoes, an upper-trimming cutter, a support for said cutter movable about an axis extending widthwise of a shoe to cause the cutter to trim off the surplus margin of the toe end of the upper and thereafter reversely movable to starting position, an ejector for engaging the waste material removed from

the upper, a support for said ejector movable with said cutter support about the same axis in the upper-trimming operation, and means for moving said ejector support farther in the same direction about said axis to cause the ejector to eject the waste material in response to the reverse movement of the cutter support.

47. In a machine for operating on shoes, an upper-trimming cutter, a support for said cutter movable about an axis extending widthwise of a shoe to cause the cutter to trim off the surplus margin of the toe end of the upper and thereafter reversely movable to starting position, an ejector for engaging the waste material removed from the upper, a support for said ejector movable with said cutter support about the same axis in the upper-trimming operation, mechanism connected to said ejector support and movable with it, and a device into operative relation to which said mechanism is carried in the upper-trimming operation for operating said mechanism to cause the ejector to eject the waste material in response to the reverse movement of the cutter support.

48. In a machine for operating on shoes, means for lasting the toe-end portion of a shoe in a cycle of automatic operations of the machine, means constructed and arranged to receive the shoe after the toe-lasting operation and to clamp and hold the shoe independently of a cycle of operations of the machine, a cutter for trimming off the surplus margin of the toe end of the upper while the shoe is so held, and automatic means for operating said cutter thus to trim the upper under control of the next cycle of operations of the machine.

49. In a machine for operating on shoes, means for lasting the toe-end portion of a shoe in a cycle of automatic operations of the machine, means constructed and arranged to receive the shoe after the toe-lasting operation and to clamp and hold the shoe independently of a cycle of operations of the machine, a cutter for trimming off the surplus margin of the toe end of the upper while the shoe is so held, power-operated means for operating said cutter thus to trim the upper, and automatic means for initiating the operation of said power operated means by the next cycle of operations of the machine.

50. In a machine for operating on shoes, means for lasting the toe-end portion of a shoe in a cycle of automatic operations of the machine, means constructed and arranged to receive the shoe after the toe-lasting operation and to clamp and hold the shoe independently of a cycle of operations of the machine, a cutter for trimming off the surplus margin of the toe end of the upper while the shoe is so held, fluid-operated means for operating said cutter thus to trim the upper, and automatic means for admitting operating fluid to said fluid-operated means by the next cycle of operations of the machine.

51. In a machine for operating on shoes, means for lasting the toe-end portion of a shoe in a cycle of automatic operations of the machine, means constructed and arranged to receive the shoe after the toe-lasting operation and to clamp and hold the shoe independently of a cycle of operations of the machine, a cutter for trimming off the surplus margin of the toe end of the upper while the shoe is so held, power-operated means for operating said cutter thus to trim the upper under control of the next cycle of operations of the machine, and additional automatic means for effecting the release of the shoe from said

23.

clamping means also by the next cycle of operations of the machine.

52. In a machine for operating on shoes, means for lasting the toe-end portion of a shoe in a cycle of automatic operations of the machine, means constructed and arranged to receive the shoe after the toe-lasting operation and to clamp and hold the shoe independently of a cycle of operations of the machine, a cutter for trimming off the surplus margin of the toe end of the upper while the shoe is so held, fluid-operated means for operating said cutter thus to trim the upper, means for admitting operating fluid to said fluid-operated means and for thereafter releasing the fluid therefrom by the next cycle of 15

operations of the machine, and additional automatic means for effecting the release of the shoe from said clamping means also by the next cycle of operations of the machine.

Certificate of Correction

Patent No. 2,437,696.

March 16, 1948.

BERNHARDT JORGENSEN

It is hereby certified that errors appear in the printed specification of the above numbered patent requiring correction as follows: Column 9, line 50, for the word "received" read *removed*; column 12, line 8, for "lever" read *levers*; column 14, line 63, for "pressure" read *presser*; and that the said Letters Patent should be read with these corrections therein that the same may conform to the record of the case in the Patent Office.

Signed and sealed this 12th day of October, A. D. 1948.
